(57) **CLAIM**

The ornamental design for a daytime running light arrangement for a vehicle front headlamp, as shown and described.

DESCRIPTION

FIG. 1 is a front and left side perspective view of the daytime running light arrangement for a vehicle front headlamp, shown equipped on the passenger and drive side of a vehicle respectively;

FIG. 2 is a front view thereof;

FIG. 3 is a right side view thereof;

FIG. 4 is a left side view thereof;

FIG. 5 is a top view thereof;

FIG. 6 is a bottom view thereof;

FIG. 7 is a rear side perspective view thereof; and,

FIG. 8 is a rear view thereof.

The broken lines in the drawings indicate a boundary residing between claimed and unclaimed portions. The broken lines form no part of the claimed design. The claimed design is indicated by the portions shown within the broken line boundaries, while the deemphasized, grayscale portions shown outside of the broken line boundaries are environment and form no part of the claimed design.
